WASHING MACHINE

Robert J. Anderson, Sidney, Ohio

Application February 24, 1936, Serial No. 65,317

6 Claims. (Cl. 68—54)

This invention relates to a washing machine and more particularly to a washing machine comprising a tub with a mechanically operated agitator or ramp in the bottom thereof.

5 The object of the invention is to provide a washing machine of the type indicated which will efficiently wash the clothes by a combined bending and rubbing action upon the clothes while producing a movement of the mass of 10 clothes in the tub whereby every portion of that mass will be subjected to the bending and rubbing action.

Another object of the invention is to provide a ramp or agitator which will operate to redistribute the clothes continuously in both vertical and horizontal arrangement and at the same time will efficiently bend and rub the portion of the clothes subjected most directly to its action.

Another object of the invention is to combine 20 a ramp of the kind described with an oval tub whereby additional squeezing and washing action is exerted upon the clothes in the tub, while other advantages are offered by the shape of the tub.

Other objects and details of the invention will 25 appear as the description proceeds.

In the accompanying drawings forming a part of this specification, Figure 1 is an elevation of one form of apparatus embodying the invention, with portions broken away to illustrate the position 30 of the ramp within the tub and some of the construction thereof; Fig. 2 is a plan view of the uncovered tub with a portion of the ramp in section; Fig. 3 is a side elevation of the ramp; Fig. 4 is a topographical map of the ramp.

35 The machine illustrated in the drawings comprises a tub 10 having a cover 11 and supported upon a base 12. Suitable driving means, not shown, are provided for a shaft 13 which projects upward through the bottom of the tub. Upon 40 this shaft there is mounted a sleeve 14 which carries the ramp 15. This ramp comprises a circular bottom 16 with two risers 17 thereon, which are identical and, therefore, but one of which need be described. Each of these risers has one 45 approximately vertical face 18 preferably cupped as indicated at 19. The other side of the riser slopes down as indicated at 20. Preferably the riser is highest at the center 21 of the ramp and the top of side 18 as well as of 20 slopes down- 50 ward towards the shoulder 22 which rises nearly perpendicular from the circular bottom 16. On sloping side 20 there is a series of upwardly projecting curved rubbing surfaces 23 which resemble somewhat successively higher hills in a 55 mountain range, while between this and the

center of the ramp, there is a valley 24. The contour of the ramp is somewhat difficult to describe accurately or illustrate fully by perspective and sectional views and, therefore, it has been shown in Fig. 4 in the form of a topographical map, the lines from 4' to 8' indicating successive elevations.

It will be noted from Fig. 2 that the tub 10 is considerably longer one way than the other, so that the tub has an oval shape. This has certain 10 advantages which will be described in connection with the operation of the machine.

It will be readily understood that shaft 13 may be oscillated by any usual or suitable mechanism. While the magnitude of the oscillation 15 may be varied while retaining many of the advantages of the invention, it is preferred to move the ramp during each oscillation somewhat more than 180°, 215° as indicated on Fig. 2 being a very suitable distance for the movement of the 20 ramp.

Presuming the ramp to be in the position in which it is indicated in Fig. 2 and to start in an anti-clockwise direction, it will be readily understood that the approximately vertical faces 18 25 will have a tendency to give a rotational movement to the water and clothes in the tub in this anti-clockwise direction. A very considerable movement is thus imparted to the contents of the tub by the oscillation of the ramp through 30 215° or thereabouts. Upon the return movement of the ramp in a clockwise direction throughout the same arc, it will be readily understood that, at the start of the movement, the continued momentum of the water and clothes tends to 35 drag the clothes up over rubbing projections 23 and over the slope between points 21 and 22. This slope between points 21 and 22 may be made a smooth curved ridge, but preferably is rendered somewhat wavy as indicated most clearly upon 40 Fig. 4. It will be readily understood that, as the clothes are thus dragged up over projections 23, they will be given a wavy bending motion which assists in the movement of the threads of cloth giving at the same time a bending action 45 and a slight rubbing action upon the cloth. Likewise, when the goods reach the slope between points 21 and 22 they are dragged down over that slope by the suction created by hollow 19, and this fairly sharp bending is accompanied 50 with a rubbing action over the slope.

As stated, when the return or clockwise motion is started, the momentum of the water and clothes carry them up over the sloping sides 20. 55 As this momentum lessens, the movement of the

ramp in the clockwise direction continues to move the slope past the water and clothes, so that the action of the relative movement of water and clothes to the ramp continues throughout this oscillation of the ramp. Thereupon, the ramp is again oscillated in the anti-clockwise direction, once more imparting motion to the water and clothes in the tub. Of course, the clockwise motion of the ramp materially lessens the movement of the water and clothes in the anti-clockwise direction and under some circumstances may even bring it to rest so that, when the anti-clockwise movement of the ramp is started, it may result in the inertia of the water and the clothes causing some dragging up of the clothes from pockets 18 over the slope between point 21 and points 22; but for the most part, the movement of the ramp in the anti-clockwise direction is effective to impart movement of the water and clothes while the greater part of the washing action is effected during the clockwise movement of the ramp, and the resultant relative movement of the clothes with respect to the ramp.

25 While the major washing result is believed to flow from the vertical movement of the clothes by the risers on the ramp, it is found that the oval shape of the tub is advantageous, probably because it results in some horizontal alternate stretching and squeezing of the clothes as they move from the short radius to the long radius and vice versa. The shape of the ramp is such that the clothes will readily slide up the surface if any considerable amount is caught between shoulder 30 22 and the wall at the shorter diameter, so that no objectionable jamming results. At the same time sufficient action does result to aid in the washing of the clothes. It will be obvious that this will have an effect in redistributing the 35 clothes as well as in imparting a bending and squeezing action thereto.

As indicated above, it is believed that the major portion of the washing action is imparted by the relative movement of the clothes over the sloping sides 28 of the ramp, but it should be pointed out that the vertical sides 18 perform their function not only in imparting momentum to the water and clothes in the tub so as to effect said relative movement between the clothes and the sloping 45 sides of the ramp, but also during the return movement the vertical sides 18 play their part in sucking the clothes downward over the slopes from point 21 to shoulders 22. Cupped portions 50 18 aid in this sucking action and assist in causing the clothes to hug the ramp so that the ramp can continuously operate effectively thereon.

It will be readily seen that, while one form of the ramp has been shown and described in fairly minute detail, considerable variation in the construction can be made within the scope of this invention. The broadest objective is the formation of the ramp with risers arranged somewhat in the ratchet form, so that the oscillation of the ramp in one direction operates more effectively to produce rotation of the water and clothes than does the movement of the ramp in the other direction and there is produced a constant rotation of the water and clothes with respect to the ramp, each complete oscillation of the ramp thus operating upon a different section of the clothes. Also, the upward and downward movement of the clothes as they slide up sloping portion 28 and down into cups 18 rearranges the clothes and 55 gives them a rolling action whereby different

portions are brought into direct contact with the ramp. The oval shape of the tub has a further effect in varying the horizontal distribution of the clothes, as indicated above. The combination of these different effects very effectually redistributes the clothes in every direction so that all portions of the contents of the tub are thoroughly subjected to the action of the ramp and the washing and cleansing effect is produced upon the entire contents of the tub.

10 The oval shape of the tub is also a convenience from the standpoint of the operator, since it enables the operator, standing opposite the shorter radius, to approach more nearly the center of the tub than could be done with a round tub of the same capacity. This shortens the reach which is necessary in reaching for the clothes to lift them out and present them to the wringer or dryer.

20 What I claim is:

1. A ramp for a washing machine and means to oscillate the ramp, the ramp comprising a substantially cylindrical base and risers from the base, each riser having one face approximately perpendicular to the base with an undercut socket 25 therein, and having the other face sloping upward from the base towards the top of the riser, there being a depression or valley in said other face extending substantially the entire length 30 thereof.

2. An oscillatable ramp for a washing machine, said ramp having a substantially circular base being highest at the center and sloping downward from the center towards the circumference 25 of the ramp along the top of a plurality of risers, the side of each riser towards one rotational direction being approximately vertical, but having an undercut socket therein and the face of each riser towards the other rotational direction sloping upwards and having a series of projections 40 from the sloping face, the said projections rising from the sloping surface, the successively higher projections being nearer the circumference of the ramp and there being a depression between these 45 projections and the center of the ramp extending substantially the length of the sloping surface of the riser.

3. A washing machine comprising a tub oval in cross-section and a ramp mounted oscillatably in the center of the tub, said ramp having risers thereon, each riser having one face approximately vertical and having a depression between the center of the ramp and the circumference thereof, the other face sloping upwardly to the 55 top of the riser.

4. A washing machine comprising a tub oval in cross-section and a ramp mounted oscillatably in the center of the tub, said ramp having risers thereon, the risers having their faces towards one 60 rotational direction more nearly perpendicular than their faces towards the opposite rotational direction and being highest at the central portion of the ramp.

5. A ramp for a washing machine and means to oscillate the ramp, the ramp comprising a substantially cylindrical base and risers from the base, each riser having one face approximately perpendicular to the base and having the other face sloping upward from the base to the top of 70 the riser and having a depression between the center of the ramp and the circumference thereof, and the outer surface of said other face sloping downwardly to said base.

6. A ramp for a washing machine and means 75

to oscillate the ramp, the ramp comprising a substantially cylindrical base and risers from the base, the risers being highest at the center of the base, each riser having one face approximately perpendicular to the base and having the other face sloping upward from the base to the top of

the riser and having a depression between the center of the ramp and the circumference thereof, and the outer surface of said other face sloping downwardly to said base, and an undercut socket in each perpendicular face.
